LAP ROBE

William P. Sullivan, San Diego, Calif., assignor to Stephen F. Armstrong and A. G. Armstrong, partners under firm name of Polarobe Company, Green Bay, Wis.

Application June 29, 1955, Serial No. 518,908

3 Claims. (Cl. 2—69)

This invention relates generally to lap robes, and more particularly to improvements in lap robes of the wrap around type.

The purpose of this invention is to provide a lap robe that is held restricted, by the spring clamp, to a minimum, thereby facilitating the manipulation thereof; and further, to design a robe that is provided with cooperating and coacting cushion and guard covers on the respective wing portions thereof.

An object of this invention is the provision of a body clamping arrangement for a lap robe whereby the side wing portions of the robe may be facilely wrapped around a wearer without restriction by the clamping means.

Another object is to provide a body clamping arrangement for a lap robe whereby the robe may be alternatively spread out to accommodate persons seated on either side of the clamp wearer.

Yet another object is to provide a body clamping arrangement for a lap robe whereby the clamp may be alternatively pivoted 180° from its normal position, about its mounting hem, thereby to reverse the robe and enable the clamp to clasp the robe around its entirety, when desired.

Still another object of this invention is the provision of a body clamping arrangement for a lap robe whereby the robe may be conveniently folded without interference by the clamping means.

A further object of this invention is to provide a lap robe with a waterproof seat portion.

Still a further object is to provide a lap robe with an insulated seat portion.

Yet a further object is to provide a lap robe with an insulated seat portion on one of the wings and a cooperative cover guard on the other wrap around wing.

Other objects and many of the attendant advantages of this invention will be readily appreciated as the same becomes better understood by reference to the following detailed description when considered in connection with the accompanying drawings in which like reference numerals designate like parts throughout the figures thereof and wherein:

Fig. 1 illustrates a perspective view, of a preferred embodiment of the invention;

Fig. 2 shows a section of the garment taken on line 2—2 of Fig. 1, showing the spring clamp in the short hem receiving portion;

Fig. 3 shows a section of the garment taken on line 3—3 of Fig. 1, showing the seat element portion on one of the wings; and

Fig. 4 shows a section of the garment taken on line 4—4 of Fig. 1, showing the cover guard portion on the other of the wings.

Referring now to the drawings, wherein like reference characters designate like or corresponding parts throughout the several views, there is shown in Fig. 1 a lap robe garment generally indicated at 10 comprising a central body portion 11 and extended side wing portions 12 and

13. While the robe may be made of any suitable material it is preferably made of woolen textile fabric.

The upper margin of the robe is doubled back and sewed to form a hem 14, the doubled back portion being slotted at 15 and 16. Said slots are spaced to define the narrow central portion 11 of the robe, the spacing being less than the width of a wearer's waist.

A circular split spring waist clamp 17 is threaded through said slots, and is loosely disposed in that part of the hem between the slots. Said circular spring clamp is of a length sufficient, when tensioned, to approximately encircle the waist of a wearer, and is made of resilient material such as steel, plastic or the like.

Normally, the untensioned relaxed spring assumes a configuration having a circumference less than the body of the wearer; but when it is expanded so as to encircle the waist of the wearer, it becomes tensioned sufficiently to embrace the waist with a force adequate to support the robe pending therefrom.

15 The robe is generally rectangular in plan and normally used with its long axis disposed horizontally. Measured along its long axis, the robe is of a width to cover the front of the wearer and to extend to be wrapped around and lapped at the back of the wearer's body. The fold or lap at the back of the body should be ample to anchor the robe in position by the weight of the body seated upon the lapped portions of the robe.

20 Measured along its vertical axis, the robe is of a length to extend approximately from the waist to the ankles of the wearer.

25 The frontal side of the wing 13 is provided with a seat element 20, made from cushioning material or insulation material, or the like, secured thereto as by stitching. Such materials could consist of pillow fillings of all types, soft rubber, foam rubber, and insulation mats, or the like. Said seat element is located on the wing so that when the wing is wrapped around the body of the wearer, the seat element becomes disposed under the wearer so as to function as a seat for the wearer.

30 The frontal side of the remaining wing 12 is provided with a cover guard 18. The cover guard is made from wear resistant material such as leather or the like, or water resistant material such as rubber or plastic, or the like. The wear resistant material provides a good wearing surface for resisting the abrasive action of concrete seats such as found in football stadia. The water resistant material protects the overlying seat element and the wearer thereon from the dampness and wetness of water soaked wooden bleachers. Said cover guard is secured to the wing 12 as by stitching, and is located on said wing so that when said wing 12 is wrapped around the body of the wearer the guard cover 18 becomes disposed over the seat element 20. The guard cover 18 functions to 35 protect the seat element 20 when the robe is wrapped around the body of the wearer, in overlapping relation. The seat element 20 and guard cover 18 are assembled in such a manner that, when brought together in a close relation, they cooperate to produce a single result.

40 The short length of hem 14, defined by the slots 15 and 16, for receiving a small section of the spring clamp 17, provides a construction and arrangement for sharing the robe with and serving other persons, seated on either side of the robe wearer, with conventional robe comfort and protection. In this instance the robe wearer does not wrap the robe wings around himself, but in lieu thereof merely extends the wings sidewise to cover the laps of those persons seated on either side of him. The short unrestricting hem mounting provides this new feature.

45 Also, the short length of the hem 14, defined by the slots 15 and 16, for loosely receiving a small section of the spring clamp 17, provides a construction and arrangement

for reversing the robe, should that be desired. The spring clamp need only be pivoted or transited 180° over the top end of the robe to achieve such reversal. The short contained clamp section, and loose mounting in the hem, allows the spring clamp to be freely transited. This reversed arrangement results in the spring clamp being disposed exteriorly of the robe, except for the receiving hem, from whence it can be brought to bear on and embrace the robe against the body around its entirety.

The characteristic features of this invention are the short hem mounting arrangement; the provision of an insulated seat element on the robe; the provision of a seat cushion and cooperating guard cover on the respective robe wing portions; and an easily reversible lap robe construction.

Obviously many modifications and variations of the present invention are possible in the light of the above teachings. It is therefore to be understood, that within the scope of the appended claims, the invention may be practiced otherwise than as specifically described.

What is claimed and desired to be protected by Letters Patent of the United States is:

1. A lap robe, comprising: a central body portion of soft foldable material having side wing portions, each side wing portion being of a width adapted to overlap at the rear when worn by a single wearer, and to selectively accommodate and normally cover a person seated on each side of a centrally disposed robe wearer, when shared, said robe having a length adapted to extend substantially from the waist to the ankles of a wearer; a hem along the upper margin of said central body portion, said hem having spaced receiving openings in the central body portion on each side of the centerline thereof; and a substantially circular spring clamp for tensionally embracing the waist of a wearer threaded through said hem through said hem receiving openings, only the front arcuate portion of the spring clamp being received and disposed in said hem between said receiving openings, said hem and openings being larger than the spring clamp in cross section to allow said clamp to be freely pivoted in said hem for reversing the robe, said clamp adapted to extend substantially

4
around a wearer's waist when worn by a wearer to support the robe thereon.

2. The lap robe of claim 1 and a separate seat cushion on one of said wings disposed to function as a seat for a single wearer when said wing is normally worn around the body of a wearer; and a separate guard cover of wear resistant material for said cushion and of substantially the size on the other of said wings correspondingly disposed thereon to overlie said seat cushion when said other wing is worn overlapped relative to said seat cushion wing.
3. A lap robe, comprising: a central body portion having side wing portions, adapted to be worn around the body of a wearer and of a length to extend substantially from the waist to the ankles of a wearer, said wings being 15 of a width adapted to overlap each other to provide a double thickness of material substantially across the rear side of the wearer; spring clamp mounting means on the upper margin of said central body portion; a substantially circular spring clamp for tensionally embracing the waist 20 of said wearer engaged with said mounting means; a separate seat cushion on one of said wings disposed on its overlappable portion to function as a seat for a wearer when said wing is worn around the body; and a separate guard cover of wear resistant material for said cushion and of 25 substantially the same size on the other of said wings disposed on the overlappable portion thereof and correspondingly disposed thereon to overlie and cover said seat cushion when said wings are in overlapped relation on the wearer.
